UNITED STATES PATENT OFFICE.

LEONARD E. HURST AND JAMES F. MILLER, OF DETROIT, MICHIGAN.

TRUCK CONVEYER.

Application filed December 30, 1922. Serial No. 609,870.

To all whom it may concern:

Be it known that we, LEONARD E. HURST and JAMES F. MILLER, citizens of the United States, and residents of Detroit, Wayne County, Michigan, have invented a new and Improved Truck Conveyer, of which the following is a specification.

This invention relates to means for pushing trucks along tracks and particularly for causing the trucks which carry vehicle bodies and other structures to pass into and through dry kilns, baking ovens and other treating chambers, and its object is to provide a device of this character which will extend a minimum distance above and below the floor surface, which will operate regularly and automatically, and which can be constructed at low cost.

This invention consists of a guiding structure mounted between a pair of rails constituting the tracks for trucks, of an actuator slidable in said guides and a series of dogs mounted thereon adapted to engage cross bars or bolsters or other projections on the trucks, and means for causing the actuator to slide back and forth parallel to said rails, the spaces between adjacent dogs being not more than the distance through which the actuator moves back and forth and the distance between the end dogs being greater than the distance between the cross bars of two adjacent and engaging trucks which are being moved along the track.

This invention also consists in the details of construction illustrated in the accompanying drawings and particularly pointed out in the claims.

In the drawings, Fig. 1 is a plan of one unit and the motor of this improved truck conveying device. Fig. 2 is an end elevation thereof. Figs. 3 and 4 are together a side elevation thereof. Fig. 5 is a section on the line 5—5 of Fig. 1. Fig. 6 is a side elevation of a pushing dog. Fig. 7 is a side elevation of a worm wheel which actuates a pusher.

Similar reference letters refer to like parts throughout the several views.

In many industries pieces of work which have been painted, varnished or enameled, or which are to be exposed to the action of dry or moist air, or air charged with chemicals, or other articles which are to be especially treated, are loaded on trucks which travel on tracks which extend through long rooms or

chambers filled with hot or charged atmosphere, and trucks carrying such work are slowly pushed along said tracks, into one end of the chambers and out of the other, pressure being applied to the rear truck 60 which pushes all the others before it.

Several factors are of great importance. The trucks must usually be low so that the work need not be lifted more than a minimum height, which limits the road clearance, and the actuating mechanism must extend a minimum distance below the floor level so as not to cut into the concrete or tile slabs, which now usually constitute factory floors, more than a minimum amount. These 70 factors have been taken care of in the construction shown in the accompanying drawings.

The motor and main driving mechanism are shown in Figs. 1, 2 and 3 and are preferably located at one side of the work room or at some place where they will be out of the way. While practically any desired means may be employed to actuate the pushers, we prefer a motor 1 having a shaft 2 connecting to a change-speed mechanism 3 whose shaft 4 carries a bevel gear 5 meshing the bevel gear 6 at the upper end of the shaft 7. The motor and change-speed mechanism are shown mounted on a frame 8 which 75 also supports the bearings 9 for the shaft 7. A bevel gear 10 on the lower end of this shaft meshes with the gear 11 on the line shaft 12.

The dotted lines 14 in Fig. 1 indicate the walls of a treating chamber and the rails 15 extend from the place where the work is prepared, through the chamber. The work is placed on trucks 16 and pushed into the chamber. Any desired number of pairs of 95 tracks may be employed, depending upon the size of the plant and each pair of tracks is provided with its own pushing mechanism. The tracks are preferably laid directly on the floor 18 and the line shaft 12 100 is preferably laid in a groove in the floor. In modern plants the floor 18 is usually of wood laid on a slab 19 of concrete and it will usually be found desirable to notch the slab for the bevel gear 11, but this notch 105 need not be of any great depth. The line shaft extends below the rails and has a coupling 20 at one end which connects to the coupling 22 at one end of the worm 23. The coupling 24 at the opposite end of this worm 110

connects to a coupling 25 at one end of a second line shaft 26 which may drive a second conveyer, and so on.

The actuator comprises a base plate 28 having a vertical stub shaft 29 for the worm wheel 30, and two bearings 31 for the worm 23. Attached to the worm wheel is an arm 33 which carries a pin 34 that extends through an eye in one end of the connecting rod 35.

The pusher consists of a pair of angle bars 36 carrying pins 37 on which the dogs 38 are mounted. These dogs are normally held in the position shown in Fig. 6 by the counterweights 39, but which permit the dogs to swing down to pass an obstruction. At any number of points these angle bars are attached to plates 40 which are slidable in the guides 42 mounted on brackets 43 resting on the floor. A yoke 44 connects to adjacent ends of these angle bars and carries a pin 45 which extend through an eye at the other end of the connecting rod 35. If desired, a shield 46 may be used to cover the actuating mechanism.

The trucks are usually low on the floor and those shown in the drawings have side sills 50 supporting the horses 51 and also having cross pieces or bolsters 52 and 53, the latter supporting the stirrups 54 for the wheels 55. The bolsters 53 are sufficiently low to be engaged by the dogs 38, as indicated in Fig. 4, and the distance between the bolsters 53 of each truck and the distance between adjacent bolsters of two adjacent trucks is always less than the distance between the end dogs on the angle bars 36. The distance between dogs is equal to or less than but not more than the distances the dogs travel, that is, the stroke of the pusher. Any other desired trucks may be used.

When a truck is loaded, the workmen open the doors of the chamber and push in the truck. The dog 38 engages a bolster 53 on the truck and pushes the truck up against the next truck in advance and thus pushes along all the trucks on the track. The speed of the line shaft will depend upon the length of the chamber and the time the work is to remain therein. When the foremost truck reaches the exit door it is pulled out and the door closed. It is evident that by properly proportioning the worm gear and the parts connected thereto, any desired speed may be obtained.

The details of construction, the proportions and sizes of the various parts, and the number and arrangement of these truck con-

veyers may all be changed by those skilled in the art without departing from the spirit 60 of my invention as set forth in the following claims.

We claim:—

1. In a conveyer for trucks, a pair of tracks for the truck wheels, guides between the tracks, a pair of bars slidably mounted in the guides, dogs mounted on the bars and adapted to engage projections on the trucks, and means to move the bars back and forth.

2. In a conveyer for trucks, a pair of tracks for the truck wheels, guides between the tracks, a pair of bars slidably mounted in the guides, dogs mounted on the bars and adapted to engage projections on the trucks, and means to move the bars back and forth 70 comprising a worm wheel, a vertical shaft on which said worm wheel is mounted, means to rotate the worm wheel, a crank pin mounted on the worm wheel and a connecting rod extending from the crank pin to said bars. 80

3. In a conveyer for trucks, a pair of tracks for the truck wheels, guides between the tracks, a pair of bars slidably mounted in the guides, dogs mounted on the bars and adapted to engage the projections on the 85 trucks, and means to move the bars back and forth, the distances between adjacent dogs being not more than the distances said dogs move back and forth.

4. In a conveyer for trucks, a pair of tracks for the truck wheels, guides between the tracks, a pair of bars slidably mounted in the guides, dogs mounted on the bars and adapted to engage projections on the trucks, and means to move the bars back and forth. 90 the distances between adjacent dogs being not more than the distances said dogs move back and forth and the distance between the end dogs on said bars being greater than the distance between the projections on adjacent trucks to be engaged by said dogs. 100

5. In combination with a floor, rails laid thereon, a line shaft lying in a groove in said floor, a worm connected thereto, a bed supporting the worm, a vertical shaft mounted on the bed, a worm wheel mounted on the vertical shaft in mesh with the worm, means to rotate the line shaft and worm, a pusher and guides therefor between the rails, said pusher embodying a series of pivoted dogs adapted to swing in a vertical plane, a crank pin on the worm wheel, and a connecting rod extending therefrom to the pusher. 110
